UNITED STATES PATENT OFFICE.

PERRY OKEY, OF COLUMBUS, OHIO.

SELF-STARTER FOR AUTOMOBILES.

1,204,814.

Specification of Letters Patent. Patented Nov. 14, 1916.

Application filed March 20, 1914. Serial No. 825,967.

To all whom it may concern:

Be it known that I, PERRY OKEY, a citizen of the United States of America, and residing at Columbus, in the county of Franklin 5 and State of Ohio, have invented certain new and useful Improvements in Self-Starters for Automobiles, of which the following is a specification.

My invention relates to self-starters for 10 automobiles and consists in the production of a simple mechanism operating through the medium of an inertia element to throw a starting motor into coöperative relation to the fly-wheel of the engine without material 15 jar or undue stress upon the motor. With the utilization of simple and direct clutching apparatus, I effect a smooth but efficient coupling of the starting motor to engine fly wheel, and yet the connection is such owing 20 to the improved features of my apparatus, that this starting motor may be thus connected or disconnected without any danger of sticking or wedging.

My improvement is of primary importance 25 because of its simplicity and because of the direct connection to the engine of which the starting motor is capable. No excessive mechanism is required, for the main essentials of the invention are a feed shaft, 30 a friction clutch connecting such feed shaft to the starting motor, an inertia pinion-element automatically movable with the initial rotation of the feed shaft upon which it is threaded to engage or disengage with a 35 rack on the fly-wheel of the engine, and abrupt checking elements to check the pinion element in its endwise movement in such a manner as to obviate danger of subsequent sticking or wedging.

The principal features of my invention, 40 in so far as any of the features may be segregated from a combination which is practically essential to success may be said to be the checking means and the friction clutch device. The first insures free operation of the parts without wedge action and the second relieves the parts from strain which would otherwise be seriously detrimental.

The preferred embodiment of my invention is shown in the accompanying drawings in which similar characters of reference designate corresponding parts and in which,

Figure 1 is a side elevation, partially broken away, of my improved starting apparatus with the pinion element shown in inoperative position and prior to the setting

of the starter in operation. Fig. 2 is a detail in elevation with the pinion element shown in operative position, and Fig. 3 is a section taken on line 3—3 of Fig. 1.

In the drawings, the usual crank shaft is shown at 1 and carried upon this crank shaft is a fly-wheel 2 having a rack upon its outer periphery as at 3, the rack in this case being made integral although not necessarily so. Supported from the crank shaft casing 4 in any suitable manner as at 5 is a bearing 6 which is desirably of a type to reduce friction as much as possible.

The bearing supports a feed shaft 7 having a feed screw 8 throughout a portion of its length and carrying upon its opposite end a disk enlargement 9 fitting in a clutch yoke 10. The inner face of the clutch yoke is provided with a friction surface of 75 leather or other material as at 11 and adjacent to the outer face of the disk enlargement is a sliding ring 12 faced with friction material as at 13. The clutch elements are maintained in operative relation by a coil 80 spring 14 embracing the shaft 7 and bearing against the ring 12 at one end and against the clutch yoke at its opposite end. The clutch yoke as an entity is carried upon and rotatable with the shaft of an electric motor 85 15, shown to be under the control of a switch 16.

At either end of the feed screw is a checking element rigidly secured thereto and designated 17 and 18, respectively. The operative surfaces of these checking elements are in the form of triangular teeth 19 and 20, the teeth 19 being turned in a direction opposite to the teeth 20. The pinion element is in the nature of a traveling sleeve 21 carrying a fly-wheel 22 and a pinion 23, the sleeve being threaded to fit upon and be moved by the feed screw 8. Both ends of the traveling sleeve are provided with triangular teeth as at 24 and 25 and these teeth are 100 complementary to the teeth 19 and 20.

The operation will be apparent. Fig. 1 shows the starting mechanism in inoperative position. When the switch is closed and the motor starts to rotate, the friction 105 clutch takes hold upon the feed shaft with a comparatively gradual action and causes spinning of such feed shaft. The pinion element, because of its inertia, fails to rotate and is therefore caused to travel until 110 it meshes with the rack on the periphery of the fly-wheels 2 and is finally checked by the

checking element 18. As the engine picks up speed, the pinion element is automatically kicked out of mesh with the main fly-wheel 2.

- 5 The principal advantages would seem to reside not only in the friction clutch and checking devices but also in the provision of a perfectly balanced mechanism. A vital consideration in this would seem to reside in the miniature fly-wheel 22 which gives the necessary inertia and at the same time insures the proper balance of the parts throughout the operation.

Having thus described my invention, 15 what I claim as new is:

1. A self-starter for gas engines and the like comprising a feed shaft, a motor, a driven element, a driving element movable by said feed shaft between operative and 25 inoperative positions due to its inertia and rotation of said feed shaft, and a fly-wheel for accentuating the inertia of said driving element.
2. A self-starter for gas engines and the

like comprising a feed shaft, a motor, a 25 driven element, a floating driving element movable by said feed shaft between operative and inoperative positions due to its inertia and rotation of said feed shaft, a fly-wheel to increase such inertia, an interposed 30 friction clutch, and elements checking said driving element at either end of its movement, said checking elements being free from checking surfaces of a frictional nature.

3. A self-starter for gas engines and the like comprising a feed shaft, a motor, a driven gear, and a fly-wheel inertia element movable along and by said feed shaft and carrying a driving gear, and checking elements for said traveling fly-wheel.

In testimony whereof I, hereby, affix my signature in presence of two witnesses.

PERRY OKEY.
